[57] CLAIM

The ornamental design of a portable machinery analyzer, as shown and described.

DESCRIPTION

FIG. 1 is a perspective view of a portable machine analyzer showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a right side elevation view thereof;

FIG. 7 is a left side elevation view thereof; and,

FIG. 8 is a top plan view of an alternate embodiment of a portable machine analyzer showing my new design all views not shown are identical to those shown in FIGS. 2, 3, and 5-7.

The broken line showing is for illustrative purposes only and forms no part of the claimed design.
